United States Patent

Des. 236,856
Patented Sept. 16, 1975

236,856

BACK PACK COOLER

Fidelis L. Miller, 961 S. Ash, Tempe, Ariz. 85281

Filed Dec. 18, 1973, Ser. No. 425,737

Term of patent 14 years

Int. Cl. D3—02

U.S. Cl. D87—1 R

FIG. 1 is a perspective view of the top, back and one end of a back pack cooler showing my new design with cover in place; and

FIG. 2 is an exploded perspective view of the front, other end and bottom of the back pack cooler shown in FIG. 1 with the cover removed.

I claim:

The ornamental design for a back pack cooler, as shown and described.
